CLAIM

The ornamental design for a folded wheel block, as shown and described.

DESCRIPTION

FIG. 1 is a perspective view of the folded wheel block showing our new design;

FIG. 2 is an enlarged top plan view thereof;

FIG. 3 is a side elevational view thereof, the opposite side being a mirror image thereof;

FIG. 4 is a bottom plan view thereof;

FIG. 5 is an end elevational view of the right end of FIG. 3;

FIG. 6 is a left end elevational view of FIG. 3; and FIG. 7 is a sectional view taken along the line 7—7 of FIG. 4.

The design of the folded wheel block is characterized with a bottom plate having laterally spaced pairs of downwardly directed triangular projections located at opposite ends and the midsection of the bottom plate.

FIG. 1***FIG. 2***
